DESIGN FOR A CASING FOR A SUCTION CLEANER OR SIMILAR ARTICLE

Frank L. Pierce, North Canton, Ohio, assignor to The Hoover Company, North Canton, Ohio,
a corporation of Ohio

Application June 13, 1936, Serial No. 63,287

Term of patent 14 years

To all whom it may concern:

Be it known that I, Frank L. Pierce, a citizen of the United States, residing at North Canton, in the county of Stark and State of Ohio, have invented a new, original, and ornamental Design for a Casing for a Suction Cleaner or Similar Article, of which the following is a specification, reference being had to the accompanying drawing, forming a part thereof.

The figure is a perspective of a casing for a suction cleaner or similar article, showing my new design, the essential feature of the design residing in the surface ornamentation.

I claim:

The ornamental design for a casing for a suction cleaner or similar article, as shown and described.

FRANK L. PIERCE.
